UNITED STATES PATENT OFFICE.

FRANK M. STEINER AND WALTER S. GRAVES, OF MINNEAPOLIS, MINNESOTA, ASSIGNEES TO STEINER SALES COMPANY, OF SALT LAKE CITY, UTAH, A CORPORATION OF UTAH.

DESIGN FOR A TOWEL CABINET.

Application filed January 11, 1923. Serial No. 4,859. Term of patent 3½ years.

To all whom it may concern:

Be it known that we, FRANK M. STEINER and WALTER S. GRAVES, citizens of the United States, residing at Minneapolis, in the county of Hennepin and State of Minnesota, have invented a new, original, and ornamental Design for Towel Cabinets, of which the following is a specification, reference being had to the accompanying drawing, forming a part thereof.

The figure is a perspective view of a towel cabinet showing our new design.

We claim:

The ornamental design for a towel cabinet, as shown.

FRANK M. STEINER.
WALTER S. GRAVES.
